UNITED STATES PATENT OFFICE.

JULIUS BAUER AND CHARLES KOENIGSBERG, OF CHICAGO, ILLINOIS.

TOBACCO PIPE.

Application filed May 21, 1923. Serial No. 640,306.

To all whom it may concern:

Be it known that we, JULIUS BAUER and CHARLES KOENIGSBERG, citizens of the United States, residing, respectively, at Chicago, in the county of Cook and State of Illinois, and at Chicago, in the county of Cook and State of Illinois, have jointly invented certain new and useful Improvements in Tobacco Pipes, of which the following is a specification.

This invention relates to tobacco pipes.

One object of the invention is to provide a construction of tobacco pipe which will be well adapted for production in aluminum or other suitable metal, particularly in the matter of avoiding heating of the exterior surface of the pipe to a degree which would render it uncomfortable to handle and also in the matter of rendering the construction sufficiently light to adapt it to be held in the smoker's mouth without inconvenience. In realizing this object, the pipe is made with a bowl to contain the charge of tobacco and a surrounding body wall through which the pipe is handled, which, while largely supported by the bowl is so connected therewith and spaced therefrom that transmission of heat, whether by conduction or by radiation across the intervening space, is reduced well below that which is dissipated by radiation from the body wall; the connection between the shell or surrounding wall and the bowl being limited to the top margin of the bowl and being of greatly reduced section so that the heat conducting capacity between the bowl and the shell is very small, and the body wall being so shaped that the space between it and the bowl is comparatively large. In order that these characteristics may be embodied in a substantial and durable construction, the bowl is supported upon a specially constructed base which receives the stem of the pipe, and from which the bowl is made separable. In some forms the surrounding wall will be extended upwardly to and united with the lower portion of the base; moreover, if desired, openings may be provided in the connection of the wall both with the upper margin of the bowl and with the base, in order to still further reduce the sectional area of the metal through which the heat is conducted.

Another object of the invention is to render a pipe, constructed generally as aforesaid, self righting, so that if laid on one

side it will assume an upright position. To this end, the body wall is made substantially spherical, and the base with its stem-receiving barrel, and upon which the bowl is mounted and to which, in the preferred embodiment the said wall is united, is merged with the spherical wall at the lower pole of the sphere and is made sufficiently heavier than the bowl to cause it to act as a counterweight.

The invention consists in the features of novelty exemplified in the illustrative embodiments of the invention hereinafter described, and particularly pointed out in the claims.

In the accompanying drawings—

Figure 1 is a vertical central section of one embodiment of the pipe, the plane of section being coincident with the axis of the stem-receiving barrel.

Figure 2 is a vertical central section in a plane at right angles to Figure 1.

Figure 3 is an end elevation as seen from the right of Figure 1.

Figures 4 and 5 are views similar to Figures 1 and 2 showing a modified construction.

Figures 6 and 7 are, respectively, a top plan view and a bottom plan view of the embodiment shown in Figures 4 and 5; and

Figure 8 is a vertical section showing a further modification.

Referring to Figures 1 to 7, 1 represents a base constructed with a smoke chamber 2 and a stem barrel 3 in communication with said chamber. 4 represents a bowl fitted to the base 1 over the smoke chamber 2, in any suitable manner that will cause the base to remain in assembled relation, such, for instance, as by means of screw threads 5. The bowl 4 has upon its lower end, within the smoke chamber 2, a reduced end 6 with a diametric bore that intersects the lower end of the bowl cavity and provides smoke ducts 7 through which the cavity of the bowl communicates with the smoke chamber 2.

Supported upon the upper margin 4^a of the bowl 4, depending therefrom and surrounding the bowl with a substantial intervening space 8, is a wall 9 that extends downwardly beyond the bottom of the bowl and provides a relatively cool body through which the pipe may be comfortably handled while in use. Wall 9 has no direct connection with the bowl 4 except at the top margin 4^a, where the section of the connecting

wall is such as to greatly reduce the heat transmitted by conduction. The bowl constitutes the support for the wall or a substantial portion thereof, the bowl being in turn supported upon and in upstanding relation to the base 1. Wall 9 may be, and preferably is, further supported by uniting it with the base 1 at the lower margin of the wall, well below the bottom of the bowl 4, except at the portion of the wall 9 which is intersected by the stem-barrel 3.

Preferably the general form of the body of the pipe afforded by the surrounding wall 9 is spherical or spheroidal, with the lower longitudinal line of the barrel 3 coincident with the lower pole of the sphere and extending tangentially therefrom so that the center of gravity of the pipe as a whole is below the center of the sphere and the pipe is rendered self-sustaining in an upright position and self-righting in case it should be laid upon its side; the circular section of the body in a plane transverse to the axis of the stem-receiving barrel constituting the surface upon which the pipe rolls under the over-balancing load of the tangentially united base and stem barrel; and the barrel bracing it against tipping in a vertical longitudinal plane.

Referring particularly to Figures 4 to 7, the union of the spheroidal wall 9 with the top margin 4^a of the bowl 4 may be greatly reduced in conductive section by providing a circular series of apertures 10 which reduce the separating connection of the wall 9 at the bowl 4 to narrow necks 11 of any suitable number. Similarly, the connection of the lower margin of the wall 9 with the base 1 may be reduced in conductive area by means of a slot 12 of any suitable design (herein shown as horse-shoe shape) conforming closely to the contour of the base 1 except where interrupted by the stem barrel 3.

When the bowl 4 is made removable from the base 1 and provided, of course, the wall 9 is united with the base in addition to being supported on the bowl, said wall is divided equatorially as at 13 or on some other equivalent lines, and this permits the separation of the bowl from the base and thus gives access to the smoke chamber 2 for cleaning same.

Some of the advantages of the invention can be realized, at least to a measurable degree, by the form of construction such as shown in Figure 8, in which the bowl 4^x and the base 1^x constitute an integral structure with the smoke chamber 2^x formed therein by coring or otherwise, and serving as well to receive the stem 14. In this form of all metallic spaced radiating wall pipe, wall 9^x extends integrally from the upper margin 4^a of the bowl, first outwardly to develop a substantial space 8^x, and then down-

wardly to a point below the bottom of the bowl where it terminates in completely spaced relation to the base 1^x.

We claim:

1. A tobacco pipe, comprising a substantially spherical hollow body divided equatorially into upper and lower substantially hemispherical body members, a stem socket, the lowermost surface of which is substantially tangential to the lower body member, a base member carried by and presented axially upward within said lower body member and in communication with said stem socket, and a bowl extending downwardly within and supporting the upper body member; said bowl being releasably united to the base and holding the two body members together.

2. In a tobacco pipe, a base constructed with a smoke chamber and a stem socket, a bowl supported upon and upstanding from said base and having a duct through which it unites with the smoke chamber of the base, and a body wall united to and supported from the top margin of the bowl and extending therefrom downwardly around the bowl with a substantial intervening space, and providing a heat radiating surface of a capacity in excess of the capacity for conduction of heat from the margin of the bowl to said wall; said wall being also united with the base below the bottom of the bowl and being of a substantially spherical form, with the base lying adjacent to the pole of the sphere which is opposite to the mouth of the bowl, the base having a weight relatively to that of the bowl which throws the center of gravity of the pipe below its geometrical center and thereby renders the pipe self-righting.

3. In a tobacco pipe, a base constructed with a smoke chamber and a stem barrel, a bowl supported upon and upstanding from said base and having a duct through which it communicates with the smoke chamber of the base, and a body wall surrounding the bowl, with a substantial intervening space; said wall being united to and supported from the top margin of the bowl and extending therefrom downwardly around the bowl with a substantial intervening space and providing a heat radiating surface of a capacity in excess of the capacity in excess of the capacity for conduction of heat from the margin of the bowl to said wall; said wall being also united with the base below the bottom of the bowl and being of substantially spherical form; the lower portion of the base being coincident with the lower surface of the spherical body; the stem barrel extending therefrom tangentially to the sphere of the wall; and the base and its stem barrel constituting a counterpoise that renders the pipe self-righting both in a

plane transverse to the axis of the barrel as well as in the plane of said axis.

4. In a tobacco pipe, a base constructed with a smoke chamber and a stem socket, a bowl supported upon and upstanding from said base and having a duct through which it communicates with the smoke chamber of the base, and a body wall united to the top margin of the bowl and extending therefrom downwardly around the bowl with a substantial intervening space and providing a heat radiating surface of a capacity in excess of the capacity for conduction of heat from the margin of the bowl to said wall; the bowl being separable from the base and constituting the upper closure for the smoke chamber.

5. In a tobacco pipe, a base constructed with a smoke chamber and a stem socket, a bowl supported upon and upstanding from said base and having a duct through which it communicates with the smoke chamber of the base, and a body wall united to the top margin of the bowl and extending therefrom downwardly around the bowl with a substantial intervening space and providing a heat radiating surface of a capacity in excess of the capacity for conduction of heat from the margin of the bowl to said wall; said wall being also united with the base below the bottom of the bowl; the bowl being separable from the base; and the portions of the surrounding wall that are secured, respectively, to the bowl and to the base, being also separable.

6. In a tobacco pipe, a base constructed with a smoke chamber and a stem socket, a bowl separably supported upon and upstanding from said base and having a duct through which it communicates with the smoke chamber of the base, and a substantially spherical body wall enclosing the bowl and base; said wall being divided equatorially into upper and lower portions, respectively, united to and supported from the top margin of the bowl and the base, and extending from their respective supporting members downwardly and upwardly around the bowl and base, with substantial intervening space and providing heat radiating surface of a capacity in excess of the capacity for conduction of heat from the bowl and base to said wall.

7. In a tobacco pipe, a base constructed with a smoke chamber and a stem socket, a bowl separably supported upon and upstanding from said base and having a duct through which it communicates with the smoke chamber of the base, and a substantially spherical body wall enclosing the bowl and base; said wall being divided equatorially into upper and lower portions, respectively, united to and supported from

the top margin of the bowl and the base, and extending from their respective supporting members downwardly and upwardly around the bowl and base, with substantial intervening space and providing heat radiating surface of a capacity in excess of the capacity for conduction of heat from the bowl and base to said wall; apertures being provided between the wall and the bowl to reduce the conductive area of the connections through which the wall is separated.

8. In a tobacco pipe, a base constructed with a smoke chamber and a stem socket, a bowl separably supported upon and upstanding from said base and having a duct through which it communicates with the smoke chamber of the base, and a substantially spherical body wall enclosing the bowl and base; said wall being divided equatorially into upper and lower portions, respectively, united to and supported from the top margin of the bowl and the base, and extending from their respective supporting members downwardly and upwardly around the bowl and base, with substantial intervening space and providing heat radiating surface of a capacity in excess of the capacity for conduction of heat from the bowl and base to said wall; apertures being provided between the wall and the bowl and also between the wall and the base to reduce the conductive area of the connections through which the wall is separated.

9. In a tobacco pipe, a base constructed with a smoke chamber and a stem socket, a bowl separably supported upon and upstanding from said base and having a duct through which it communicates with the smoke chamber of the base, and a substantially spherical body wall enclosing the bowl and base; said wall being divided equatorially into upper and lower portions, respectively, united to and supported from the top margin of the bowl and the base, and extending from their respective supporting members downwardly and upwardly around the bowl and base, with substantial intervening space and providing heat radiating surface of a capacity in excess of the capacity for conduction of heat from the bowl and base to said wall; the wall being spaced from the base except near the intersection of the stem barrel with the wall, thereby reducing the conductive area of its connection with the base and providing an opening into the internal space of the wall.

Signed at Chicago, Illinois, this 19th day of May, 1923.
